H. F. Lavigne,
A. Gaudreault.
By *John Murphy Jr.* Attorney

UNITED STATES PATENT OFFICE.

HENRY F. LAVIGNE AND ALDRIC GAUDREAU, OF PLAINFIELD, CONNECTICUT.

CHECK SPRING FOR LOOMS.

Application filed March 25, 1922. Serial No. 546,726.

To all whom it may concern:

Be it known that we, HENRY F. LAVIGNE, a citizen of the United States, and ALDRIC GAUDREAU, a subject of the King of Great Britain, residing at Plainfield, in the county of Windham and State of Connecticut, have invented certain new and useful Improvements in Check Springs for Looms; and we do hereby declare the following to be a full, clear, and exact description of the invention, such as will enable others skilled in the art to which it appertains to make and use the same.

The invention has for its object to prolong the life of pickers and picker sticks by keeping them straight in the middle of the lay to prevent injury to the filling by obviating the usual knocking off and cutting of the same, to prevent throwing out of the shuttle and a banging thereof and finally to prevent waste of material and insure a saving of labor and the production of more and a better grade of goods.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a side elevation of a check spring embodying the invention, showing the same applied,

Figure 2 is a central horizontal section thereof, on the line 2—2 of Figure 1, and

Figure 3 is a detail section on the line 3—3 of Figure 1, looking to the right as indicated by the arrows.

Corresponding and like parts are referred to in the following descriptions and designated in the several views of the drawings by like reference characters.

The device comprises complementary strips 1 and 2, preferably of wood. The strips 1 and 2 are connected by a substantially U-shaped frame 3 of spring material, whereby the strips are adapted to yield laterally. The U-shaped spring frame 3 is preferably

constructed of a strip of spring metal which is doubled upon itself. Bolts 4 and 5 or analogous fastening means connect the strips to the side arms or members of the frame 3. Spring plates 6 are disposed along the inner sides of the strips 1 and 2 and are attached at their outer ends thereto by means of the bolts or fastenings 4. The spring plates 6 are free throughout the remainder of their length and are adjusted laterally by means of set screws 7 mounted in the strips 1 and 2 and in the side members of the spring frame 3. The set screws 7 are secured in the adjusted position by means of jam nuts 8.

Packing 9 is applied to the inner opposing faces of the spring plates 6 and packing 10 is applied to the inner side of the closed end or bridge of the spring frame 3. This packing may be of any suitable material and preferably consists of stout leather so as to resist wear and obviate noise. One of the strips, as 2, and the corresponding side member of the spring frame 3, are cut away as indicated at 11, to provide clearance for the bolt 12 which connects the back of the box to the lay 13 of the loom. The distance between the side members of the check may be regulated to suit different sizes of pickers and picker sticks.

What is claimed is:

1. A check for picker sticks consisting of a frame having side arms, strips disposed against the inner surfaces of said side arms, spring plates to be engaged by the picker stick, said spring plates being arranged longitudinally of and intermediate the strips, fastenings passing through said side arms, and plates adjacent one end of the plates, the opposite ends of the plates being free, and adjustable means passing through the side arms and strips adapted to abut the plate to tension and position them.

2. A check for picker sticks consisting of a frame having side arms and a bridge connecting them, strips disposed against the inner surfaces of said side arms and terminating short of the bridge, spring plates to be engaged by the picker stick, said spring plates being arranged longitudinally of and intermediate the strips, bolts passing through said side arms, strips and plates adjacent one end of the plates, packing dis-

posed against said spring plates and through which said bolts also pass, the opposite ends of the plates being free, bolts adjustable through the side arms and strips adapted to abut the plates to tension and position them, and packing disposed against the inner surface of the bridge and beyond said spring plates.

In testimony whereof we affix our signatures in presence of two witnesses.

HENRY F. LAVIGNE.
ALDRIC GAUDREAU.
